UNITED STATES PATENT OFFICE.

LAURENCE E. TOPHAM, OF SWAMPSCOTT, MASSACHUSETTS, ASSIGNOR TO UNITED SHOE MACHINERY COMPANY, OF PATERSON, NEW JERSEY, A CORPORATION OF NEW JERSEY.

SHOE-SEWING MACHINE.

1,191,747.

Specification of Letters Patent. Patented July 18, 1916.

Application filed October 30, 1912. Serial No. 728,579.

To all whom it may concern:

Be it known that I, LAURENCE E. TOPHAM, a citizen of the United States, residing at Swampscott, in the county of Essex and State of Massachusetts, have invented certain new and useful Improvements in Shoe-Sewing Machines; and I do hereby declare the following to be a full, clear, and exact description of the invention, such as will enable others skilled in the art to which it appertains to make and use the same.

The invention relates to sewing machines, and more particularly to curved hook needle sewing machines for sewing inseams of boots and shoes. In machines of this class during a cycle of operations of the machine in sewing a seam, starting with the needle in retracted position with a loop of thread held in its hook, the needle advances through the previously formed loop and through the materials, and after it has reached its advanced position the thread is laid in the hook of the needle by the looper. When the needle retracts, a loop of thread is drawn through the material and through the preceding loop which, when the needle advanced, lay about the shank of the needle. In order that the shoe may be removed when the seam has been completed and another shoe placed in position to be sewed, it is essential that the needle be retracted out of engagement with the work. Before the shoe can then be removed, the loop of thread last formed must be removed from the barb of the needle. In order to free the last loop from the barb of the needle and bring the needle to rest out of engagement with the work, in the machines heretofore devised, it has ordinarily been necessary for the operator to manipulate either the shoe or the machine. Certain automatic mechanisms have been devised for accomplishing these results by arresting the forward movement of the machine when the needle has executed at least a portion of its work penetrating movement, and then reversing the direction of movement of the main driving shaft of the machine and thereafter causing the shaft to come to rest when the needle is retracted out of engagement with the work.

The primary object of the present invention is to produce a curved hook needle inseam shoe sewing machine provided with mechanism for placing the thread and the

parts of the machine in such a condition as 53 to permit the ready removal of the shoe from the machine and the placing of another shoe in position to be sewed, without reversing the rotation of the main shaft of the machine.

With the above object in view, the invention contemplates the provision in a machine of this class of mechanism to free the last needle loop from the stitch forming devices during the forward rotation of the 65 main shaft and thereafter to arrest the forward rotation of the main shaft and stop the machine with the needle in retracted position out of engagement with the work. In the preferred embodiment of the invention the 70 last needle loop is freed from the stitch forming devices by rendering the looper inactive during the last cycle of operations before the main shaft is brought to rest.

The machine is provided with mechanism 75 for advancing and retracting the welt guide during each cycle of operations, and a further feature of the invention contemplates the provision of means for causing an increased retracting movement to be imparted to the welt guide as the forward rotation of the main shaft is arrested. By this provision the welt guide is brought to a position such that it presents no obstacle to the ready removal of the shoe or the insertion of another shoe in the machine.

Another feature of the invention contemplates the provision of means acting automatically to actuate the tension device to release the tension on the thread as the forward rotation of the main shaft is arrested, to allow the removal of the work from the machine.

Further features of the invention consist of certain constructions, arrangements and 95 combinations of parts, the advantages of which will be obvious to one skilled in the art from the following description.

The various features of the invention will be readily understood from an inspection of 100 the accompanying drawings and the following detailed description of the mechanism illustrated therein.

In the drawings, Figure 1 is a side elevation of the head of a welt and turn shoe 105 sewing machine embodying the features of the invention in their preferred forms, illustrating the parts of the machine in the posi-

tions which they occupy during the sewing operation; Fig. 2 is a plan of a portion of the head of the machine, showing the parts in the positions which they assume after the machine has been brought to rest at the completion of the sewing operation, with a part of the casing broken away and parts of the mechanism shown in section; Fig. 3 is a side elevation of a portion of the machine illustrating particularly the mechanism for actuating the looper and the mechanism for rendering the looper inactive, showing the parts in the positions which they assume after the treadle has been released to stop the machine, but before the machine has been brought to rest; Fig. 4 is a side elevation of a portion of the machine illustrating particularly the mechanism for actuating the welt guide, the parts being shown in the positions which they occupy during the sewing operation; Fig. 5 is a side elevation of the mechanism illustrated in Fig. 4, showing the parts in the positions which they occupy when the machine has been brought to rest; Fig. 6 is a side elevation of the mechanism illustrated in Fig. 3, showing the parts in the positions which they assume when the machine has been brought to rest; Fig. 7 is a view in vertical section of the mechanism shown in Fig. 6, looking toward the rear of the machine; Fig. 8 is a sectional view taken on the line 8—8 of Fig. 6; Fig. 9 is a rear elevation of the mechanism illustrated in Fig. 4, together with a portion of the mechanism for arresting the rotation of the shaft; and Fig. 10 is a side elevation of the complete machine.

In the drawings, the invention is illustrated as embodied in a welt and turn shoe sewing machine for sewing the inseams of boots and shoes, such as shown and described in the patent granted to Andrew Eppler, No. 1,108,560, dated August 25, 1914. This machine is provided with a curved hook needle 1, a looper 2, a thread finger 3, a welt guide 4 and a back gage 5, and a feed point and channel guide not shown, and these devices are operated through suitable connections by cams carried by the main shaft 6 of the machine. As is usual in this type of machine, the main shaft makes one revolution for each cycle of operations performed by the stitch forming and work feeding devices. During the sewing operation, the machine is driven through a belt pulley 7 secured to the end of the main shaft and connected by a driving belt 8 with a pulley 9 mounted upon the base of the machine. The pulley 9 is connected by means of the bevel gears 10 with a sleeve 11 mounted on the driving shaft 12 and carrying one member 13 of the main driving clutch. The driving shaft carries the other member 14 of the clutch and also carries the driving pulley 15, through which motion is imparted

ed to the driving shaft. The engagement of the members of the driving clutch is controlled through a treadle 16 connected with the clutch operating wedge 17. When the treadle is depressed, the members of the driving clutch are forced into engagement and the machine is driven at a speed depending upon the pressure which the operator applies to the treadle. When the treadle is released, the clutch members are disengaged, thus disconnecting the main shaft of the machine from the driving shaft. The upward movement of the treadle when it is released also throws into operation the mechanism which brings the machine to rest with the parts in proper position for the removal of the shoe. This mechanism in the construction shown comprises a friction clutch consisting of the clutch members 18 and 19. The clutch member 18 is formed on a spiral gear 20 which is loosely mounted on the cam shaft 6 and is driven at a constant slow speed, in the same direction as the direction of rotation of the main shaft during the sewing operation by a spiral pinion 21 secured to a shaft 22. The shaft 22 is continuously driven from the driving pulley 15 through a belt 23 passing over a pulley formed on the hub of the pulley 15 and over a pulley 24 secured to the shaft 22. The other member 19 of the clutch is formed on a flange 25 projecting from a sleeve 26 which is loosely mounted upon the cam shaft 6. The sleeve 26 is free to slide longitudinally on the shaft but is connected to rotate with the shaft by means of a block 27 secured to the pulley 7 and arranged between lugs 28 projecting radially from the sleeve 26. The sleeve is held normally in position with the clutch members out of engagement by a spring 29 arranged in a recess in the block 27 and interposed between the bottom of the recess and the head of a bolt which carries a plate 30 engaging the lugs 28.

The clutch member 18 is driven at a constant speed, as stated above, and the speed of this member is very slow compared with the speed of rotation of the cam shaft of the machine during the sewing operation. Therefore when the clutch members 18 and 19 are engaged, they act as a friction brake to absorb the energy due to the momentum of the cam shaft and of the machine until the speed of rotation of the main shaft is the same as that of the clutch member 19. After this has occurred, the clutch member 18 acts as a driving member for the clutch member 19 and the main shaft, and the main shaft is thereby rotated in a forward direction at slow speed until the stopping devices act to bring the main shaft to rest with the needle and other parts of the stitch forming mechanism in the proper position for the removal of the shoe. The stopping devices are constructed and arranged so that the

clutch members 18 and 19 are engaged and disengaged at definite points in a cycle of operations of the machine and after the clutch members are engaged, the main shaft 5 executes a definite movement before it is brought to rest. The mechanism for engaging and disengaging the members of the clutch at the proper time in the rotation of the main shaft comprises a cam groove 32 formed in the sleeve 26 and engaged by a roll on one arm of a bell crank lever 33. The other end of the bell crank lever is provided with a recess 34 adapted to receive a locking pin 35 which is normally 10 held out of engagement with the lever so that during the normal running of the machine the lever is oscillated idly by the cam. The locking pin is mounted in the end of a slide 36 which is held in normal position by a spring 37. The spring surrounds a bolt or rod 38 extending from the rear of the slide and is interposed between a shoulder on the slide and the inner end of an adjustable screw threaded sleeve 39 through 15 which the rod 38 passes, the sleeve being threaded into a suitable portion of the frame. The rod 38 is held in position to maintain the spring under compression by the engagement of a nut 39^a threaded on the rod with an arm 40 projecting from a fixed bracket on the frame of the machine, the arm being provided with an aperture through which the rod passes. The locking pin is forced in a direction to engage it 20 with the bell crank lever by a spring 41 and the lower end of the pin is connected with the treadle 16 so that the pin is held down out of engagement with the bell crank lever so long as the treadle is depressed and 25 the driving clutch is acting to drive the main shaft of the machine. A latch 42 is also connected with the lower end of the locking bolt and is arranged to engage a shoulder 43 on the slide 36 and hold the locking bolt in its lower position until the treadle has been raised sufficiently to allow the locking bolt to engage the recess in the arm of the bell crank lever. In the construction shown, the latch 42 is loosely pivoted on the rock shaft 44 and is connected with the shaft by a pin projecting through a slot in the hub of the latch. The rock shaft 44 is mounted in a block 46 secured on the lower end of the locking bolt and carries an arm 47 which is connected by a link 48 with the treadle 16. When the treadle is depressed, the rock shaft 44 turns until the latch 42 brings up against the slide 36, and then during the continued downward 50 movement of the treadle the locking bolt is drawn down against the tension of its spring. This carries the latch 42 below the shoulder 43. When the treadle is released, the latch 42 prevents the upward movement 55 of the locking pin and the rock shaft 44 is

rocked until the pin strikes the end of the slot in the hub of the latch and swings the latch outward, thus disengaging it from the shoulder 43. When this takes place the spring forces the pin upward against the 70 under side of the bell crank lever, and when the hole in the lever registers with the pin, the pin snaps up into the hole, thus connecting the lever with the slide 36.

The cam 32 is so timed that the hole in the 75 end of the bell crank lever is brought into position to register with the locking pin at the proper time in the cycle of operations of the stitch forming mechanism. When the pin is engaged with the bell crank lever, the 80 lever is held from movement about its pivot, and the cam 32 acting on the roll carried by the lever shifts the clutch sleeve 26 to bring the members 18 and 19 of the clutch into engagement. When the lever and slide 36 are 85 locked together by the locking pin, the movement of the lever is resisted by the spring 37, and the force with which the members of the friction clutch are pressed together will depend upon the tension of the spring. In 90 the construction shown, the parts are so timed and controlled that the locking bolt is engaged with the lever and the friction clutch engaged while the needle is retracted, and the forward rotation of the main shaft is continued thereafter until the needle has 95 penetrated the work, and then retracted out of engagement with the work, at which time the clutch members are disengaged and the rotation of the shaft is arrested, thereby 100 bringing the parts of the machine to rest. When the clutch members 18 and 19 have been engaged by the action of the cam 32, the main shaft is first slowed down to the slow speed of the member 18 of the clutch by the 105 braking action of the members of said clutch, and the rotation of the main shaft is then continued in a forward direction at slow speed for substantially a complete revolution, or until the shaft again arrives at a 110 point where the cam 32 acted to engage the members of the clutch, when the opposite portion of the cam from that which caused the engagement of the clutch members causes the clutch members to be again disengaged. Simultaneously with the disengagement of 115 the clutch members, the motion of the cam shaft is arrested by a suitable brake so that the needle executes substantially a full cycle of its movement after the friction clutch is 120 engaged and the needle is brought to rest in retracted position out of engagement with the work. The main shaft is therefore brought to rest with the needle in its retracted position and the other parts of the 125 stitch forming mechanism in such positions that they do not interfere with the removal of the shoe. When the friction clutch is disengaged, the forward movement of the main shaft is finally stopped by a friction brake 130

which is applied to a brake disk on the main shaft of the machine. In the construction illustrated in the drawings, the brake consists of a brake strap 49^a arranged to engage the surface of a brake disk 50^a, the forward extremity of which strap is attached at a fixed point on the framework of the machine, and the rear extremity of which is secured to the vertical arm of the lever 49 pivoted to a shaft 50 secured in the machine frame.

As above described the machine is brought to rest with the needle in retracted position during the forward rotation of the main shaft and during a forward cycle of movement of the machine, and mechanism is provided for rendering the looper inactive during the last cycle of movement of the needle before the main shaft of the machine is brought to rest, so that the needle is retracted while its hook is empty, and is free of thread when it is brought to rest out of engagement with the work. In the present embodiment of the invention this mechanism is actuated in timed relation to the parts of the machine and to the devices for arresting the forward rotation of the shaft, by suitable connections from the mechanism for engaging the members of the braking and slow speed forward driving mechanism, and for disengaging said members and stopping the machine. In the construction illustrated in the drawings the looper is provided with a shank which is received in a cylindrical socket formed in the lower end of an arm 51, the connection between the looper shank and the arm being such that the looper can be adjusted vertically. The shank of the looper is held in the arm by means of a clamping screw 52. The arm 51 is pivoted midway its length to a block 53 secured to the forward end of a cam actuated slide 54. The slide 54 is arranged above the needle to reciprocate in a plane parallel with the plane of the needle, so that the reciprocating movements of the slide impart forward and rearward movements to the looper. The movements of the looper at right angles to the plane of the needle are produced by oscillating the arm 51, the movements of the looper due to the reciprocation of the slide and the oscillation of the arm acting to carry the thread around the needle and lay it in the barb. The upper end of the arm 51 is provided with a socket in which a rod 55 is received. This rod is provided at its upper end with a socket or bearing which receives a rod 56 secured to an arm 57 projecting from a rock shaft 58 arranged parallel with the slide 54. The rod 55 is free to slide in the socket in the upper end of the arm 51, and the rod 56 is free to slide in the socket in the upper end of the rod 55, so that the arm 51, can be oscillated from the rock shaft 58 and at the same time the slide 54 can be reciprocated. The shaft 58 is provided with a downwardly

projecting arm 59 at its rear end which is provided with a roll engaging a cam on the cam shaft of the machine.

In the illustrated embodiment of the invention the looper is rendered inactive by causing the looper to operate in a single plane only during the last cycle of movement of the needle before the main shaft of the machine is brought to rest. To this end the slide 54 is constructed of independently movable parts 60 and 61, of which the part 60 is arranged to slide within the part 61, as illustrated particularly in Figs. 1, 3 and 7. The parts 60 and 61 of the looper slide 54 are connected by a linkage or toggle mechanism consisting of the links 62 and 63. When the machine is running normally the linkage 62-63 is maintained in the position illustrated in Fig. 1, so that the two parts of the looper slide move forwardly and rearwardly in unison, thereby imparting the proper forward and rearward movements to the looper. When the looper is thrown out of action, the movement of the rear cam actuated part 61 of the looper slide is absorbed in the relative angular movement of the parts of the linkage 62-63, so that substantially no forward and rearward movements are imparted to the part 60 of the looper slide. The linkage 62-63 is maintained in the position illustrated in Fig. 1 during the normal operation of the machine by a tilting pin 64 mounted upon an arm 65 attached to a rock shaft 66 journaled in a bearing in a bracket 67. The link 63 of the linkage carries a pin 68, to the end of which is attached a sleeve 69 which is arranged to slide on the tilting pin 64. During the normal operation of the machine the tilting pin 64 is maintained in a position substantially parallel with the slide 54, thereby maintaining the linkage 62-63 in the position illustrated in Fig. 1, and causing the two parts of the looper slide to move in unison. The looper is thrown out of action by tilting the pin 64 into the position illustrated in Fig. 3. When the tilting pin occupies this position, and the part 61 of the looper slide is moved forwardly under the action of the cam, the sleeve 69, guided by the tilting pin, moves downwardly at an angle with relation to the looper slide, carrying the linkage 62-63 to the position illustrated in Fig. 3, thereby absorbing the forward movement of the rear part of the looper slide in the angular movement of the parts of the linkage, so that substantially no forward movement is imparted to the looper. When the part 61 of the looper slide is moved rearwardly, the linkage is again brought to the position illustrated in Fig. 1. It will therefore be observed that while the tilting pin is maintained in the position illustrated in Fig. 3, substantially no forward and rearward

movements will be imparted to the looper. In the construction illustrated the tilting pin is moved from a position parallel with the looper slide to the position illustrated in Fig. 3 at the time when the members 18 and 19 of the friction clutch are engaged by suitable connections with the rod 38.

A crank arm 70 is carried by the outer end of the rock shaft 66, and is connected by a link 71 with the lower arm 72 of a lever mounted upon the shaft 73 which supports the cam lever for operating the thread finger. The upper arm 74 of this lever is provided with a fork in which is received a block 75 carried by a pin 76 which is mounted in a block 77 adjustably carried between nuts 39^a and 78 upon the outer end of the rod 38. When the members of the friction clutch are engaged by the cam 32, the rod 38 is moved outwardly through the sleeve 39. This movement of the rod through the connections described operates to tilt the tilting pin 64 into the position illustrated in Fig. 3. The machine is timed so that this occurs when the part 61 of the looper slide is retracted, and the parts are so arranged that at this time the axis of the pin 68, which carries the sleeve 69, and the axis of the rock shaft 66 are in alinement; therefore the tilting of the pin does not affect the relative positions of the links 62 and 63. When, however, the rear part of the looper slide advances, the movement of this part of the slide is absorbed in the relative angular movement of the parts of the linkage, as above described, but at each retracting movement of the rear member of the looper slide the linkage is restored to the position illustrated in Fig. 1. When the cam 32 operates to disengage the members of the friction clutch, at which point the shaft is brought to rest, the rod 38 is returned to its initial position illustrated in Figs. 1 and 6. This movement of the rod restores the tilting pin to the position illustrated in Fig. 6 through the mechanism described, so that when the machine is brought to rest the parts of the looper mechanism are in position ready to start their normal operation when the machine is started.

The mechanism with which the machine is provided for applying the brake strap 49^a to the surface of the brake disk which it is arranged to engage comprises a linkage or toggle consisting of the links 79 and 80, of which the link 79 is connected to the upper extremity of the lever 49. The link 80 is provided with a slot at its forward extremity which receives a pin 81 carried by the upper end of an arm 82 on the lever 72-74. The link 80 is provided with an arm 83 which is connected by a comparatively light tension spring 84 with the arm 82. When the machine is performing its normal operation the linkage 79-80 is main-

tained in the position illustrated in Fig. 1 by the pressure of the pin 81 against the end of the slot in the link 80, the tension of the spring 84 not being sufficient to straighten the linkage. At this time the coiled spring 85 surrounding the hub of the lever 49 operates to maintain the brake strap in a slackened condition, as shown in Fig. 1. When the rod 38 moves to the right in Fig. 1 upon the engagement of the members of the friction clutch, the forward movement of the pin 81 in the slot in the link 80 relieves the pressure upon the forward portion of the linkage 79-80, and the coiled spring 84 then acts to straighten the linkage, as shown in Fig. 3. When the rod 38 is returned to the left upon the separation of the members of the friction clutch, the arm 82 of the lever 72-74 is moved to the left (Fig. 1), and the engagement of the pin 81 in the end of the slot in the link 80 forces the linkage 79-80 to the left, thereby moving the lever 49 in a direction to apply the brake strap 49^a to the surface of the brake disk 50^a. The forward movement of the main shaft, which is then rotating at slow speed, is thereby quickly arrested without shock or jar.

The tension devices of the machine illustrated in the drawings are of well-known construction, and comprise a tension wheel 95 at the rear of the machine, a brake disk 86 fast upon the shaft of the tension wheel, a friction brake shoe 87 bearing upon the periphery of the brake disk, a pivoted lever 88 to one end of which the brake shoe is connected, and a spring pressed rod 89 connected to the other end of the lever. In order that the tension may be released when the machine is brought to rest, the lever 49 is provided with an arm 90, and to this arm is pivotally connected the upper end of a rod 91 which extends downwardly through a hole in the end of the brake shoe carrying lever 88, and is provided with an adjustable nut 92 arranged to engage the brake shoe carrying lever to move the brake shoe from the friction disk. The rod 91 is pressed upwardly by means of a coiled spring 93. When the lever 49 is moved to the left to apply the brake strap 49^a to the surface of the cam disk, the arm 90 is depressed, thereby releasing the tension.

The welt guide 4 is mounted upon the lower end of a pivoted welt guide carrying arm 94 which is connected by a link 95 to the welt guide slide 96. The welt guide is yieldingly advanced by a coiled spring 97 engaging a pin on the welt guide slide in the usual manner, and is retracted at the proper time in the operation of the machine by a lever 97^a connected by a link 98 with a clutch box 99 surrounding the slide, and provided with the usual clutch mechanism for engaging the slide. The back rest 5 is carried on the forward extremity of the back 130

rest slide 100 which is moved forward by the usual spring 101. The mechanism for locking the back rest and welt guide slides is of the usual construction, and comprises 5 clutch rolls 102 and 103, arranged to engage suitable friction surfaces on the welt guide and back rest slide respectively, a wedge shaped supporting member 104 for the rolls pivoted to the arm of the cam actuated lever 105 provided with an arm 106 carrying a cam roll which engages a cam on the cam shaft of the machine, which cam actuates the lever to release the slide. The lever is actuated to lock the slides by a tension spring 10 107 connected at one extremity with the arm 105 of the lever, and at the other with a fixed point on the machine frame.

The welt guide of the machine is advanced and retracted during each cycle of 20 operations in substantially the same manner as in the machine of the Eppler patent referred to above. In the present invention, however, mechanism is provided for causing an increased retracting movement to be im- 25 parted to the welt guide as the forward rotation of the main shaft of the machine is arrested to permit the ready removal of the shoe and the insertion of another shoe in the machine. The mechanism for actuating 30 the welt guide is illustrated particularly in Figs. 1, 4 and 5. The lever 97^a is pivoted at 108 on the machine frame, and is provided with a rearwardly extending arm 109. An arm 110 is pivoted at 111 to the arm 109 35 of this lever, and is provided at its outer extremity with a cam roll which engages a cam on the cam shaft of the machine. A linkage or toggle consisting of links 112 and 113 connects the arm 109 of the lever 97^a 40 with the vertical arm of the lever 49, and the arm 110 is connected with the central joint of said linkage by a link 114. The position of the welt guide mechanism when the machine is in normal operation is illus- 45 trated in Fig. 4, the parts being shown in said figure in the positions which they assume when the welt guide is advanced. It will be noted from an inspection of this figure that when the vertical arm of the 50 lever 49 is in forward position, the oscillatory movements of the arm 110 cause very little change in the relative angular positions of the links 113 and 114, the arm 110, links 113 and 114, and lever 97^a all oscillat- 55 ing in unison substantially as one. Referring to Fig. 5, it will be seen that when the vertical arm of the lever 49 is in back position, the oscillatory movement of the arm 110 from the position in which it is shown 60 in Fig. 4, to that in which it is shown in Fig. 5, will cause an angular movement of the links 113 and 114 such as to diminish the angle between said links. The lever 97^a will thereby be operated to retract the welt guide

to a position to the rear of its normal re- 65 tracted position when the machine is brought to rest, so as to permit the shoe to be easily removed from the machine and another shoe to be placed in position to be sewed.

At the completion of the sewing of a seam the thread leading from the thread handling devices to the shoe is severed by a suitable knife, and the free end of the thread is inserted between the gripping devices which 70 hold the free ends of the thread during the formation of the first stitch. Since the machine is brought to rest with the needle in retracted position, when the machine is again started into operation the takeup immediately begins its loop drawing stroke. This action of the takeup, if exercised while the tension is applied to the supply end of the thread, would operate to draw the free 75 end of the thread from the gripping devices 80 and interfere with the proper formation of the first stitch. It is therefore desirable that the tension be maintained in released condition until after the takeup has completed its first loop drawing stroke. It is 85 however desirable upon starting the machine that the brake strap 49^a be slackened so that it will not frictionally engage the co-acting surface of the brake disk. In order 90 to slacken the brake strap when the treadle 95 is depressed to start the machine, without causing the tension to be applied, the brake strap is connected with the lever 49 by means of a rotatable eccentric 115, carried by the shaft 116 which connects the brake 100 strap with the lever. An arm 117 is attached to the shaft 116 and is provided at 105 its extremity with a slot which receives the end of the pin 118 which connects the link 48 with the arm 46. When the treadle is 110 depressed to start the machine, the engagement of the pin 118 in the slot in the arm 117 causes said arm to be actuated to rotate the eccentric 115 and thereby slacken the 115 brake strap 49^a. When the treadle is released the arm 117 is actuated in the opposite direction, thereby rotating the eccentric 115 in a direction to tighten the brake strap. This movement of the eccentric is, however, not sufficient to engage the brake strap with 120 the surface of the brake disk, since there is considerable slack in the brake strap at this time. After the takeup has completed its loop drawing stroke, the linkage 79-80 is broken so as to permit the spring 85 to operate the lever 49 in a direction to permit the tension to be restored to the supply end of the thread, and to return the parts of the welt guide mechanism to their normal 125 positions. It will be noted from an inspection of Fig. 5 that when the machine has been brought to rest, the link 79 lies against a collar carried by the cam shaft of the

- machine, which collar forms a stop to limit the movement of the link 79 when the linkage is straightened. After the takeup has completed its loop drawing stroke the link 5 79 is lifted to break the linkage 79--80 by a cam 119 carried by the cam shaft. When the linkage is broken the lever 49 is moved to the right under the influence of the spring 85, thereby lifting the arm 90 to permit the tension to be restored to the thread, and restoring the parts of the welt guide actuating 10 mechanism to the position illustrated in Fig. 4. This movement of the lever 49 also causes the brake strap to be completely slackened.
- 15 Having explained the nature and object of the invention, and particularly described one form of machine in which it may be embodied, what is claimed is:—
1. A chain stitch shoe sewing machine, 20 having, in combination, stitch forming devices including a hook needle and a looper, a main shaft from which said devices are operated, and mechanism to render the looper inactive during a forward cycle of 25 movement of the machine and to cause the main shaft thereafter to come to rest with the needle in retracted position out of engagement with the work.
2. A chain stitch shoe sewing machine, 30 having, in combination, stitch forming devices including a hook needle and a looper, a main shaft from which said devices are operated, and mechanism to render the looper inactive during the forward rotation 35 of the shaft and thereafter to arrest the forward rotation of the shaft and thereby the movements of the parts of the machine when the needle is in retracted position out of engagement with the work.
3. A chain stitch inseam shoe sewing machine, having, in combination, stitch forming devices including a hook needle and a looper, a welt guide, means to advance and retract the welt guide during each cycle of 45 operation, a cam shaft mechanism for causing the needle to retract while its hook is empty and come to rest out of engagement with the work during the forward rotation of the cam shaft and means operated during 50 the forward rotation of the cam shaft for imparting an increased retracting movement to the welt guide.
4. An inseam shoe sewing machine, having, in combination, stitch forming devices, 55 a welt guide, mechanism for advancing and retracting the welt guide during each cycle of operations, a main shaft, and means actuated by the forward movement of the shaft for causing an increased retracting movement 60 to be imparted to the welt guide to permit the removal and insertion of the work.
5. An inseam shoe sewing machine, having, in combination, stitch forming devices, a main shaft from which said devices are 65 actuated, a welt guide, means to advance and retract the welt guide during each cycle of operations, and mechanism for causing an increased retracting movement to be imparted to the welt guide as the forward rotation of the shaft is arrested to stop the 70 machine.
6. An inseam shoe sewing machine, having, in combination, stitch forming devices, a welt guide, mechanism for advancing and retracting the welt guide during each cycle 75 of operations of the machine, a tension device, a main shaft and mechanism actuated by the forward rotation of the main shaft of the machine to actuate the tension device to release the tension on the thread and to cause an increased retracting movement to be imparted to the welt guide to permit the 80 removal and insertion of the work.
7. A chain stitch inseam shoe sewing machine, having, in combination, stitch forming 85 devices including a hook needle and a looper, a welt guide, mechanism for advancing and retracting the welt guide during each cycle of operations of the machine, a tension device, mechanism to cause the needle 90 to retract while its hook is empty and come to rest out of engagement with the work during a forward cycle of movement of the machine, and mechanism for actuating the tension device to release the tension and for 95 causing an increased retracting movement to be imparted to the welt guide as the needle is brought to rest.
8. A chain stitch shoe sewing machine, having, in combination, stitch forming devices including a hook needle and a looper, 100 means to operate the looper in a plane substantially perpendicular to the plane of the needle, a cam actuated slide for imparting movements to the looper in a plane substantially parallel with the plane of the needle comprising independently movable parts, a connection between one of said parts and the looper, means to connect said parts so that they move in unison, and means to 105 throw out said connecting means so that substantially no movement is imparted to the part of said slide connected with the looper.
9. A chain stitch shoe sewing machine, 110 having, in combination, stitch forming devices including a hook needle and a looper, means to impart movements to the looper in a plane at right angles to the plane of the needle, a cam actuated slide for imparting 115 movements to the looper in a plane parallel with the plane of the needle comprising independently movable parts, one of which is cam actuated, a connection between the other of said parts and the looper, a linkage connecting said parts so that they operate in unison, and mechanism for causing the 120 movements of the cam actuated part of the

- slide to be absorbed in a relative angular movement of the parts of the linkage so that substantially no movement is imparted to the part of the slide connected with the 5 looper.
10. A chain stitch shoe sewing machine, having, in combination, stitch forming devices including a curved hook needle and a looper, a cam actuated slide for imparting movements to the looper in a plane parallel with the plane of the needle comprising independently movable parts, one of which is actuated by the cam, a connection between the other of said parts and 15 the looper, a linkage connecting said parts, means to maintain the linkage normally in a relatively straightened condition comprising a tilting pin normally extending parallel with the direction of movement of the 20 slide, a slide block arranged to slide on said pin and connected with the linkage, and mechanism for tilting the pin to cause a relative angular movement of the parts of the linkage during the movements of the 25 cam actuated part of the slide so that substantially no movement is imparted to the part of the slide connected with the looper.
11. A shoe sewing machine, having, in combination, stitch forming devices, a main 30 shaft from which said devices are actuated, a tension device, and positively operating means acting automatically to actuate the tension device to release the tension as the forward rotation of the shaft is arrested to 35 stop the machine.
12. An inseam shoe sewing machine, having, in combination, stitch forming devices, a welt guide, means to advance and retract the welt guide during each cycle of operations, a tension device, a main shaft, means to arrest the forward rotation of the shaft, and means acting automatically to actuate the tension device to release the tension and to cause an increased retracting movement 45 to be imparted to the welt guide as the forward rotation of the shaft is arrested.
13. A chain stitch inseam shoe sewing machine, having, in combination, stitch forming devices including a curved hook 50 needle, a looper, a welt guide, means to advance and retract the welt guide during each cycle of operations, a tension device, a main shaft, means to render the looper inactive during a forward cycle of movement 55 of the machine and thereafter to arrest the rotation of the shaft when the needle is in retracted position out of engagement with the work, and means acting automatically to actuate the tension device to release the 60 tension and to cause an increased retracting movement to be imparted to the welt guide as the shaft is brought to rest.
14. An inseam shoe sewing machine, having, in combination, stitch forming de-
- vices, a welt guide, a welt guide slide, a lever for actuating the slide, and mechanism for actuating the lever comprising a cam operated arm pivoted on the lever, a toggle connecting the arm with the lever, a second lever connected with the central joint of the toggle, means to maintain the second lever in one position during the normal operation of the machine, and means to change the position of the second lever upon stopping the machine to cause an increased re- 70 tracting movement to be imparted to the welt guide before the machine is brought to rest.
15. A chain stitch shoe sewing machine, having, in combination, stitch forming de- 75 vices including a curved hook needle and a looper, a drive shaft from which said de- vices are actuated, braking and slow speed forward driving mechanism for the shaft, means to throw said mechanism into action at a predetermined point in a cycle of operations and to throw said mechanism out of action and stop the machine, and means to render the looper inactive.
16. A chain stitch shoe sewing machine, having, in combination, stitch forming de- 80 vices including a curved hook needle and a looper, a main shaft from which said de- vices are actuated, braking and slow speed forward driving mechanism for the shaft, means to throw said mechanism into operation and to throw said mechanism out of operation and stop the machine at a pre- 85 determined point in a cycle of movement of the machine, and means to render the looper inactive.
17. A chain stitch shoe sewing machine, having, in combination, stitch forming de- 90 vices including a curved hook needle and a looper, a main shaft from which said de- vices are actuated, braking and slow speed forward driving mechanism for the shaft, means to throw said mechanism into opera- 95 tion in a cycle of operations of the machine before the thread is laid in the barb of the needle, and to throw said mechanism out of operation and stop the machine when the needle is retracted out of engagement with the work, and means to render the looper in- 100 active.
18. A chain stitch shoe sewing machine, having, in combination, stitch forming de- 105 vices including a curved hook needle and a looper, a main shaft from which said de- vices are actuated, braking and slow speed forward driving mechanism for the shaft, means to throw said mechanism into opera- 110 tion and to throw said mechanism out of operation and stop the machine at predeter- 120 mined points in a cycle of movement of the machine, and means to render the looper in- 125 active.
19. An inseam shoe sewing machine, hav-

ing, in combination, stitch forming devices, a main shaft from which said devices are actuated, a tension device, a welt guide, means to advance and retract the welt guide 5 during each cycle of operations, braking and slow-speed forward driving mechanism for the shaft, means to throw said mechanism into action and to throw said mechanism out of action and stop the machine, means to 10 actuate the tension device to release the tension and to cause an increased retracting movement to be imparted to the welt guide as said mechanism is thrown out.

20. A chain stitch shoe sewing machine, 15 having, in combination, stitch forming devices including a curved hook needle and a looper, a main shaft from which said devices are actuated, braking and slow speed forward driving mechanism for the shaft, 20 means to throw said mechanism into and out of action, and means to render the looper inactive.

21. A shoe sewing machine, having, in combination, stitch forming devices, a take-up, a main shaft from which said devices are actuated, a tension device, automatically 25 operating mechanism to actuate the tension device upon stopping the machine to release the tension, and means to cause the tension 30 to be restored after the takeup completes its first loop drawing stroke upon starting the machine.

22. A chain stitch shoe sewing machine, 35 having, in combination, stitch forming devices including a curved hook needle and a looper, a main shaft from which said devices are operated, mechanism including a timing cam to render the looper inactive during a forward cycle of movement of the 40 machine and to arrest the rotation of the shaft and stop the machine with the needle in retracted position out of engagement with the work.

23. A chain stitch shoe sewing machine, 45 having, in combination, stitch forming devices including a curved hook needle and a looper, a main shaft from which said devices are actuated, devices for arresting the forward rotation of the shaft at a predetermined point, and means to render the looper inactive at least a predetermined 50 interval before the rotation of the shaft is arrested.

24. A chain stitch shoe sewing machine, 55 having, in combination, stitch forming devices including a curved hook needle and a looper, a main shaft from which said devices are actuated, devices for arresting the forward rotation of the shaft at a predetermined point, and means including a timing 60 device for throwing the arresting devices into action and for rendering the looper inactive at a predetermined point in a rotation of the shaft.

25. A chain stitch shoe sewing machine, 65 having, in combination, stitch forming devices including a curved hook needle and a looper, a main shaft from which said devices are operated, mechanism to check the rotation of the shaft and thereafter to rotate 70 the shaft at slow speed to stopping position, and means including a timing device for throwing said mechanism into action and for rendering the looper inactive at the same point in the rotation of the shaft. 75

26. A chain stitch shoe sewing machine, having, in combination, stitch forming devices including a curved hook needle and a looper, a main shaft from which said devices are actuated, devices for arresting the 80 forward rotation of the shaft comprising means to check the rotation of the shaft and thereafter to rotate the shaft at slow speed to stopping position, mechanism including a timing device to throw said means 85 into action and for throwing said means out of action and stopping the machine at predetermined points, and means controlled by the timing device to render the looper inactive when said means are thrown into 90 action.

27. A chain stitch shoe sewing machine, having, in combination, stitch forming devices including a curved hook needle and a looper, a main shaft from which said 95 devices are actuated, devices for arresting the forward rotation of the shaft constructed to cause the shaft to execute at least a predetermined forward movement after said arresting devices are thrown into action before the shaft is brought to rest, and means including a timing device to throw the arresting devices into action and simultaneously to render the looper inactive. 100

28. A chain stitch shoe sewing machine, 105 having, in combination, stitch forming devices including a hook needle and a looper, a main shaft from which said devices are operated and mechanism acting, when thrown into operation, to free the last needle loop 110 from the stitch forming devices during the forward rotation of the shaft and to bring the shaft to rest in predetermined position with the needle in retracted position out of engagement with the work. 115

29. An inseam shoe sewing machine having, in combination, stitch forming devices, a welt guide, a welt guide slide, means including a toggle for actuating the slide to advance and retract the welt guide during 120 each cycle of operations and to retract the welt guide to the rear of its normal retracted position upon stopping the machine.

30. A shoe sewing machine, having, in combination, stitch forming devices, including a hook needle and a looper, a main shaft from which said devices are operated, stopping devices for arresting the rotation of 125

the shaft and means to render the looper inactive.

31. A shoe sewing machine, having, in combination, stitch forming devices, a tension device automatically operating mechanism to release the tension upon stopping the machine acting to maintain the tension in

released condition until the takeup has completed its first loop drawing stroke upon starting the machine.
